UNITED STATES PATENT OFFICE

RUSSELL I. MANN, OF COOPERSBURG, PENNSYLVANIA, ASSIGNOR TO MORRIS L. SOFRANSEY, OF ALLENTOWN, PENNSYLVANIA

WALL PAPER PASTING MACHINE

Application filed April 28, 1930. Serial No. 448,014.

This invention relates to pasting machines, and more particularly to an apparatus for pasting wall papers.

An important object of the invention is to provide an apparatus of this character which may be readily and cheaply manufactured and which will provide a pasting means eliminating the ordinary objections of such machines in that it prevents tearing of the paper 10 and piling up of paste in such manner that it passes to the outer face of the paper.

In the ordinary wall paper pasting machine it is necessary that the paste-applying medium, usually in the form of a roll, be made of 15 a length equal to the largest size of wall paper which is to be pasted. When shorter sizes are used, portions of the paste-applying means are exposed, with the result that no paste is removed from these portions and a 20 considerable quantity, accordingly, collects thereon finally passing from these portions to the upper surface of the paper.

A further and more specific object of the present invention is the provision of a structure 25 of this character wherein means are provided for removing paste from unused portions of the roll.

A further object of the invention is to provide an apparatus of this character which 30 may be very readily and rapidly cleansed.

A further object of the invention is the provision of a structure of this character having means whereby the paper may be moved out 35 of contact with the paste-applying medium at all times when paste is not actually being applied thereto, thereby preventing collected paste from soaking the paper to such an extent that it tears readily and can be handled only with considerable difficulty.

A still further object of the invention is to provide an apparatus of this character in which the paste-holding vat, in which the operating means is arranged, can be made of 45 relatively small size and still contain as much paste as the vat of the ordinary pasting apparatus.

A still further object of the invention is to provide apparatus of this character having 50 the paper roll mounting means of such con-

struction that the roll may be very readily applied and removed.

These and other objects I attain by the construction shown in the accompanying drawings wherein, for the purpose of illustration, I have shown a preferred embodiment of my invention and wherein:

Fig. 1 is a side elevation of the machine;

Fig. 2 is a sectional view showing the paste applying mechanism;

Fig. 3 is a plan view of the machine with the web and clamping means removed; and

Fig. 4 is a fragmentary sectional view showing the paper elevated from contact with the paste roll.

Referring now more particularly to the drawings, the numeral 10 generally designates a vat, the side walls 11 and 11—a of which have at one end thereof a pair of projecting arms 12 and 12—a mounting a paper roll shaft 13. Arising from arms 12 and 12—a are a pair of upwardly-extending arms 14 equipped at their upper ends with clamps 15 to engage a bench or table 16. The arm 12 is off-set inwardly as indicated at 17 so that its inner face lies inwardly of the inner face of the corresponding side wall 11. The paper roll shaft 13 is formed at one end with a ball element 18 fitting in a socket 19 formed in the arm 12—a and has its opposite end swingable from a position where it clears the arm 12 to a position where it is disposed at the inner end of a slot 20 formed in this arm. Adjustably mounted upon this shaft adjacent the first-mentioned end thereof is a collar 21 having a means 22 for securing the same in adjusted positions and having attached thereto one end of a spring 23 the opposite end of which bears against a disk 24 slideable upon shaft 13. When the paper roll is placed between this disk and the arm 12, the disk maintains friction thereagainst preventing too rapid unwinding of the roll or any looseness which would tend to cause misalignment.

Within the vat 10 adjacent the end wall 25 thereof most nearly adjacent shaft 13 is disposed a pasting roll 26. Pasting roll 26 is hollow, comprising a cylindrical body 27 supported at its ends by spiders 28 and 29, the 90

Within the vat 10 adjacent the end wall 25 thereof most nearly adjacent shaft 13 is disposed a pasting roll 26. Pasting roll 26 is hollow, comprising a cylindrical body 27 supported at its ends by spiders 28 and 29, the 100

openings in the spiders affording space permitting paste placed in the vat to pass to the interior of the roll. The spider 28 has a squared shank 30 adapted to engage in a socket 31 formed in the inner end of a stub shaft 32 rotatably mounted in the wall 11 and having at its outer end a pulley 33. The spider 29 has a cylindrical gudgeon 34 adapted to seat in a bearing socket 35 formed in the inner face of the wall 11—a, this wall having an inclined slot 36 extending from the top thereof to said socket, and affording a means for introducing the gudgeon 34 into the socket or removing the same therefrom.

Extending transversely of the vat in parallelism to roll 26 is a shaft 37 having at one end thereof a stationary spring-pressed blade 38 bearing upon the corresponding end of the roll and at the opposite end thereof a longitudinally-adjustable spring-pressed blade 39 bearing upon the adjacent end of the roll. Adjustment of the spring-pressed blade 39 is effected through a collar 40 slideable upon the shaft and securable in adjusted positions thereon, this collar having attached thereto one end of a spring 41 surrounding the shaft and having its opposite end secured to the blade. Shaft 37 is bodily removable from the vat, having one end held in position in the lower end of a groove 42 in the side wall 11 by means of shouldered latch springs 43 which may be sprung out of latching position to permit the shaft to be introduced to, or removed from, the lower end of the groove. The opposite end of the shaft is seated in a socket 44 formed in the wall 11—a. The front ends of the side walls have projecting upwardly therefrom a pair of arms 45 rotatably mounting a roll 46 the lower portion of the periphery of which lies slightly below a plane touching the upper end of the rear wall 25 and tangential to the pasting roll 26. One end of the roll 46 has secured thereto a pulley 47 connected by a belt 48 with the pulley 33. When roll 46 is rotated, the roll 26 will be rotated.

Between the walls 11 and 11—a is disposed a doctor bar 49 having a wiping strip 50 adapted to contact the under surface of a strip of paper passing from the pasting roll to the under surface of the roll 46. This doctor bar has its ends mounted in brackets 51 each comprising a channel closed at its lower end to afford a seat for the bar and each having a projecting stud 52 passed through an arcuate slot 53 formed in the supporting side wall 11 or 11—a. Thumb nuts 54 mounted upon the studs serve to lock the brackets in adjusted positions and to determine the tension with which the wiping strip 50 engages the sheet. From the roll 46 the paper strip passes over the upper edge of a bar 55 connecting the upper ends of arms 14 to the table 16. The upper surface of this bar is preferably slotted, or otherwise

formed as at 56 to provide a guide for the cutting knife used in severing the paper.

In order that the paper may be held out of contact with the pasting roll when the actual pasting is not taking place, the upper end of the side wall is formed with a notch 57 in which is normally disposed a transversely-extending bar 58. This bar is secured to the ends of arms 59, each of which is mounted upon a pin 60 rotatably mounted in the corresponding side wall 11 or 11—a. The outer end of one of these pins has an operating crank 61, the weight of which together with the weight of the paper bearing upon bar 58 normally tends to maintain the bar in position in notch 57. The crank 61 may, however, be swung into engagement with a frictional spring catch 62 carried by the outer face of arm 11 and when in this position will be retained against return movement until a predetermined pressure is brought to bear upon the bar. When the arm is in this position the bar 58 is elevated to an extent such that the paper web W from the roll R is lifted from the surface of pasting roll 26, thus preventing this web from collecting sufficient moisture to become weakened or stained. An additional friction means for the web is provided between the bar 58 and the roll R, this web comprising a transversely-extending carrier 63 bearing a flexible strip 64 adapted to engage against the web. The carrier 63 has its ends mounted in brackets 65 carried by the adjacent faces of arms 12, 12—a and is held in position against these brackets which are merely in the form of open seats by means of latch springs 66.

In use of the apparatus, the paper roll is placed in position upon shaft 13 and the tension means 63 is removed from its bracket 65 to permit the paper to be fed over the bar 58 and the pasting roll, and then replaced. The paper is then passed successively over the doctor bar 49, under and about roll 46, and over bar 55 to the table 16, the vat having been previously filled with paste. As the paper is drawn over roll 46, the tension applied thereto by spring 23 and by the tensioning means 63 insures rotation of roll 46 and this rotation is transmitted to the pasting roll 27 causing the same to rotate in the direction of the arrow of Fig. 2, and carry paste to and against the surface of the paper with a wiping motion. Excess paste is removed from the roll by blades 38 and 39 which have previously been properly adjusted. Roll 26 in its rotation, due to the fact that the paste enters the interior thereof, tends to assist in agitating the paste and keeping the same in properly mixed condition. When a sufficient length of pasted paper has been withdrawn, the operator severs this strip and shifts the crank 61 to its latched position. When the pasted strip has been used and a second strip is desired, he merely

grasps the severed end of the web and exerts a pull thereon. This pull must be sufficient to overcome the friction engendered by the tensioning means and the spring 23 and the tension of the latch 60 is set at such a point 5 that it will automatically release to permit bar 58 to move to its normal position prior to any movement of paper from the roll. The pasting thus continues at the point where it was previously discontinued so that there 10 are no unpasted portions on the sheet.

It will be obvious that a construction of this character may be relatively cheaply manufactured and will eliminate the objectionable features of previous devices of this 15 character.

It will also be obvious that the construction employed is capable of a certain range 20 of change and modification without in any manner departing from the spirit of my invention I; accordingly, do not limit myself to such specific structure except as herein-after claimed.

I claim:

25 In a pasting machine, a pasting means, a paper roll holder and a paper guide roll arranged at opposite sides of the pasting means, a bar between the paper roll holder and the pasting means over which the paper from a 30 paper roll supported by said holder is adapted to pass, said bar being normally disposed by gravity in a position such that it exerts no force tending to elevate the paper from the pasting means, means for shifting said bar to elevate the paper from engagement 35 with the pasting means, spring latch means for maintaining the bar in its elevated position, and means for applying tension to a paper roll upon said holding means such that the pressure applied by the paper to said bar 40 automatically disengages said spring latch to permit the bar to assume its normal position.

CERTIFICATE OF CORRECTION.

Patent No. 1,889,127.

November 29, 1932.

RUSSELL I. MANN.

It is hereby certified that the name of the assignee in the above numbered patent was erroneously described and specified as "Morris L. Sofransey", whereas said name should have been described and specified as "Morris L. Sofranscy", as shown by the records of assignments in this office; and that the said Letters Patent should be read with this correction therein that the same may conform to the record of the case in the Patent Office.

Signed and sealed this 3rd day of January A. D. 1933.
